(57)

CLAIM

The ornamental design for a terminal, as shown and described.

DESCRIPTION

FIG. 1 is a front perspective view of a terminal showing our new design;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof; and,

FIG. 8 is a rear perspective view thereof.

The broken lines are for purposes of illustrating portions of the terminal that form no part of the claimed design.

1 Claim, 8 Drawing Sheets(56)
